CLAIM

The ornamental design for an animal housing unit, as shown and described.

DESCRIPTION

FIG. 1 is a top front perspective view of an animal housing unit according to our new design.

FIG. 2 is a top rear perspective view thereof.

FIG. 3 is a left side elevation view thereof.

FIG. 4 is a front elevation view thereof.

FIG. 5 is a right side elevation view thereof.

FIG. 6 is a rear elevation view thereof; and,

FIG. 7 is a top plan view thereof.

The broken lines depict environmental subject matter, are for illustration only and form no part of the claimed design.
